(57) **CLAIM**

The ornamental design for a sound effects box for musical instrument, as shown and described.

DESCRIPTION

FIG. 1 is a top, front perspective view of a sound effects box for musical instrument showing my new design;

FIG. 2 is a top, rear perspective view thereof;

FIG. 3 is a top view thereof;

FIG. 4 is a front elevation thereof;

FIG. 5 is a right side elevation view thereof;

FIG. 6 is a left side elevation view thereof;

FIG. 7 is a rear elevation view thereof; and,

FIG. 8 is a top, front perspective view thereof showing environment.

The bottom of the sound effects box for musical instrument is flat and unornamented.

In FIGS. 1 through 7, the broken lines are for the purpose of illustrating portions of the sound effects box for musical instrument that form no part of the claimed design. In FIG. 8, the broken lines are for the purpose of showing both environment and portions of the sound effects box for musical instrument that form no part of the claimed design.
